UNITED STATES PATENT OFFICE.

COLLIN P. BRICKEY, OF LA FAYETTE, GEORGIA, ASSIGNOR OF ONE-HALF TO HUGH P. LUMPKIN, PAUL D. WRIGHT, AND RALPH A. SNOW, ALL OF LA FAYETTE, GEORGIA.

ELLIPOGRAPH.

No. 922,560.

Specification of Letters Patent.

Patented May 25, 1909.

Application filed August 19, 1908. Serial No. 449,305.

To all whom it may concern:

Be it known that I, COLLIN P. BRICKEY, citizen of United States, residing at La Fayette, in the county of Walker and State 5 of Georgia, have invented certain new and useful Improvements in Ellipsographs, of which the following is a specification.

My invention relates to an ellipsograph, and the object thereof is to provide a simple 10 and inexpensive construction which may be readily adjusted to describe circles and ellipses of different size.

In the accompanying drawing, illustrating my invention, and forming a part of this 15 specification, wherein like numerals are used to designate like parts throughout the several figures, Figure 1 is a plan view of my improved device. Fig. 2 is a side elevation thereof, and, Fig. 3 is a vertical longitudinal sectional view on an enlarged scale, taken through the overlapping ends of the swinging guide arms.

In the practical embodiment of my invention, I provide a slide plate 1, provided with 20 downturned extension pieces 2, at its ends, for supporting the same in parallel vertical spaced relation to the surface upon which an ellipse is to be described. The slide plate 1 is provided in its length, with a longitudinal slot 3, in which is mounted to slide a guide block 4, having a vertical shaft 5 projecting therethrough and through said slot 3.

Mounted with their rear downwardly offset ends 6, pivotally secured to the ends of the 25 plate 1, beyond the ends of the slot 3 thereof, are the guide arms 7 and 8, provided with inner overlapping enlarged ends 9, having longitudinal slots 10 therein, through which slots 10 of said arms 7 and 8, a bolt 11 extends. 30 The bolt 11 is loosely associated through said slots 10 and is prevented from accidental displacement by a nut 12 engaging above a washer 13, resting upon the upper surface of the upper arm 8, which arm is provided with a vertical rib 14, extending longitudinally of 35 its enlarged inner end 9, and against which the peripheral edge of said washer slides.

The bolt 11 is further provided upon its lower end beneath the arms 7 and 8, with a 40 slotted adjusting block 15, through which an adjusting bar 16 is slidably mounted, said adjusting bar 16 being secured at one end to the upper end of the vertical guide block shaft 5, and being adapted to be longitudinally adjusted through, and to be locked in its ad-

justed position with, the block 15, by a set screw 17 engaging within said block. To the lower end of the guide block shaft 5, is secured a second adjusting block 18, similar to the slot 15, and through which the pencil bar 19 is longitudinally slidably mounted, and adapted to be secured in the desired position by means of a set screw 20, engaging within said block 18.

In describing an ellipse, with my improved device, with the same in position as shown in Fig. 1, the bolt 11 is moved inwardly toward the slide plate 1, the guide block 4 being started upon its sliding movement in one direction or the other, and the movement continued until the said bolt is in the same relative position upon the opposite side of said plate 1, when as will be seen, one-half of the desired ellipse will have been drawn. The movement is then reversed, the guide 75 block 4 being started upon its travel in the same direction as heretofore, and when the said bolt 11 has reached its former position, as shown in Fig. 1, the desired ellipse is complete. From this, it will be seen that the 80 length of the pencil bar 19 from the center of the guide block shaft 5, is equal to one-half of the minor axis of the ellipse drawn, and that the sum of the lengths of the said pencil bar and the adjusting bar 16, from 85 the center of the bolt 11, inasmuch as the same must necessarily be longitudinally aligned with one another, equals one-half of the major axis of said ellipse. From this, it will be readily understood that the bolt 11 90 must move at exactly right angles to the slot 3 to describe a perfect ellipse, and in order to insure of such movement, of said bolt, I provide the enlarged ends 9 of the arms 7 and 8, with toothed racks 21, upon relatively opposite longitudinal sides of their slots 10, and I further provide the said bolt 11 with a circular toothed portion 22 to engage the said racks 21, whereby the sliding movement of said bolt, within said slots 10 of said arms 95 7 and 8, will be uniform as the said arms are 100 swung.

From the foregoing, it will be apparent that, by adjusting the length of the pencil bar 19, and adjusting bar 16, any desired size 105 and shape of ellipse may be obtained, while by adjusting the said bar 16, until the center of bolt 11 is over the center of the guide block shaft 5, a true circle of a radius equal to the length of the pencil bar 19 from said centers, 110

may be drawn. I therefore provide the adjusting block 15 with its lower face cut away in order to allow the same to be moved over the upper end of said guide block shaft 5.

5 A U-shaped rod frame 23, having the ends of its extensions rigidly secured to the down-turned extensions 2 of the slide plate 1, and provided with a centrally upwardly bent portion 24, constitutes a handle for maintaining my improved device in an upright position when in use.

Having fully described my invention, I claim:

1. In an ellipsograph, the combination of 15 a suitably supported slide plate, having an elongated slot therein, a member mounted to slide in said slot, swinging arms pivotally mounted at their outer ends adjacent the ends of said slide plate, and provided with inner 20 overlapping ends having longitudinal slots, a bolt engaging through said arm slots, to move at right angles to said slide plate slot upon the swinging movement of said arms, an adjusting bar extending from the said 25 slide member and longitudinally slidably connected to said bolt, and a pencil bar longi-

tudinally slidably connected at one end to said slide member in alinement with said adjusting bar, substantially as described.

2. In an ellipsograph, the combination of 30 a suitably supported slide plate having an elongated slot therein, a member mounted to slide in said slot, swinging arms pivotally mounted at their outer ends adjacent the ends of said slide plate and provided with inner 35 overlapping ends, having longitudinal slots, a bolt engaging through said arm slots, and slidable therein, means for insuring uniform slidable movement of said bolt within said slots, upon the swinging movement of said 40 arms, an adjusting bar extending from the said slide member and longitudinally slidably connected to said bolt, and a pencil bar longitudinally slidably connected at one end to said slide member in alinement with said adjusting bar, substantially as described. 45

In testimony whereof I affix my signature in presence of two witnesses.

COLLIN P. BRICKEY.
